F. VAN D. LONGACRE

MULTIPLE CLEARANCE CONTROL

Filed Oct. 19, 1925

INVENTOR
Frederick V. D. Longacre
BY
Herbert G. Ogden
HIS ATTORNEY

UNITED STATES PATENT OFFICE.

FREDERICK VAN DUZER LONGACRE, OF YONKERS, NEW YORK, ASSIGNOR TO INGERSOLL-RAND COMPANY, OF JERSEY CITY, NEW JERSEY, A CORPORATION OF NEW JERSEY.

MULTIPLE CLEARANCE CONTROL.

Application filed October 19, 1925. Serial No. 63,306.

This invention relates to compressors, but more particularly to clearance control for unloading the compressor.

The objects of the invention are to enable 5 clearance chambers to be simply and conveniently constructed and arranged in such manner that the clearance control may be effected in multiple, by first opening a main clearance chamber, and successively opening 10 auxiliary chambers, each communicating with the main chamber in series, but in multiple with each other. By this means multiple series control may also be obtained. In my copending application, Serial No. 15 63,307, filed October 19, 1925, I have disclosed and claimed mechanism for obtaining series clearance control.

Further objects of the invention will hereinafter appear, and to these ends the invention 20 is shown in one of its preferred forms in the accompanying drawing, which is a diagrammatic sectional elevation of a compressor cylinder having the invention applied thereto.

25 Referring to the drawing, the cylinder A is provided with the usual piston B having the piston rod C. Air or fluid to be compressed enters at the inlet D and is discharged at the discharge connection E, 30 which may be connected to a suitable receiver, not shown.

Inlet valves F and discharge valves G are of any suitable and usual construction, in this instance being shown as plate valves. 35 The compressor casing is provided with the main clearance chamber H adapted to communicate with the cylinder A through the valve opening J having a valve seat K which, in this instance, is provided with the 40 valve guide L for the main clearance valve O. A spring P tends to open the valve, which may be maintained closed in any suitable manner as by means of a pressure fluid device comprising the piston Q operating in 45 the cylinder R and having a piston rod S adapted to bear upon the valve O. Pressure fluid may be supplied to the cylinder R through the pipe T from any suitable source to maintain the main clearance valve 50 O closed, the inner or under side of the piston Q being open to atmosphere through the pipe U.

Auxiliary clearance chambers V and W, as shown, are each connected in series with

the main clearance chamber H but in multiple or parallel with each other. Valve casings X and Y are interposed between the main clearance chamber H and each of the auxiliary clearance chambers V and W, and auxiliary clearance valves a and b similar 60 in construction to the main clearance valve O control communication between the auxiliary chambers V and W and the main chamber H.

In the operation of the device let it be 65 assumed that pressure is relieved from the outer face of the main valve piston Q through the pipe T, so that the main clearance valve O opens under the influence of the spring P assisted by the pressure in the 70 cylinder, in which case the cylinder would be partially unloaded by the main clearance chamber H, which is placed in communication with the cylinder. An additional step 75 of unloading could be obtained by the opening of the auxiliary clearance valve a, which places the auxiliary clearance chamber V in series with the main chamber H. An additional step of unloading will be obtained by the opening of the auxiliary valve b, which 80 places the auxiliary chamber W in series with the main chamber H when in parallel with the auxiliary chamber V. By this means multiple clearance control is obtained for unloading purposes and in addition 85 multiple-series clearance control is secured, because the auxiliary chambers V and W are each in series with the main chamber H but in multiple arrangement with each other with respect to said main chamber. Although but two auxiliary clearance chambers 90 V and W are shown, it is to be understood that as many may be used as desired, and series of auxiliary chambers may be arranged in communication with the main 95 chamber but in multiple with each other.

I claim:

1. In a compressor, the combination of a cylinder, inlet and discharge valves, a main clearance chamber, a main clearance valve 100 between said chamber and the cylinder, and auxiliary clearance chambers and clearance valves adapted to communicate in multiple with said main clearance chamber, whereby one or more clearance chambers may be 105 opened for step-by-step unloading.

2. In a compressor, the combination of a cylinder, inlet and discharge valves, a main

clearance chamber, a main clearance valve between said chamber and the cylinder, and auxiliary clearance chambers and clearance valves adapted to communicate in series and multiple with said main clearance chambers, whereby one or more clearance chambers may be opened for step-by-step unloading.

3. In a compressor, the combination of a cylinder, inlet and discharge valves, a main clearance chamber, a main clearance valve between said chamber and the cylinder, aux-

iliary clearance chambers each adapted to communicate directly with the main chamber in series, but in multiple with each other, and auxiliary clearance valves between said auxiliary chambers and the main chamber, whereby multiple series clearance control is obtained for step-by-step unloading.

In testimony whereof I have signed this specification.

FREDERICK van DUZER LONGACRE.
